UNITED STATES PATENT OFFICE.

PATRICK H. PENDERGAST, OF SYRACUSE, NEW YORK.

DESIGN FOR A BIDET AND FOOT-BATH.

SPECIFICATION forming part of Design No. 26,331, dated November 24, 1896.

Application filed October 12, 1896. Serial No. 608,653. Term of patent 14 years.

To all whom it may concern:

Be it known that I, PATRICK H. PENDERGAST, a citizen of the United States, residing in the city of Syracuse, in the county of Onondaga and State of New York, have invented and produced a new and original Design for a Combined Bidet and Compartment Foot-Bath, of which the following is a specification, reference being had to the accompanying drawings, in which—

Figure 1 shows a top plan view of the design complete. Fig. 2 is a side view thereof. Fig. 3 is a front view thereof, these three views being deemed necessary to properly illustrate the same.

The leading feature of my design consists in a combined bidet and single compartment foot-bath just forward and at either side thereof, its configuration and form being substantially as shown in the drawings.

A is the body of the bidet, comprising vertical side walls *a* and rear walls *b*, as shown.

c is a bowl in the upper portion of the body A and having a flange *d* projecting laterally,

as shown, the top of the bidet being oblong or egg-shaped, that is, enlarged at the rear end and diminishing in size gradually as it approaches the front.

B are the compartments, having vertical side walls in extension of the side walls of the bidet, the front walls of said bidet constituting the rear walls of the foot-baths and having front walls *e* and inside walls *f*.

The sides and front walls of the foot-baths are surmounted by rounded rims *g*, substantially as shown. The corners of the bidet and foot-baths and their rims are rounded both interiorly and exteriorly, as shown.

What I claim is—

The design for a combined bidet and foot-bath substantially as herein described and shown.

In witness whereof I have hereunto set my hand this 9th day of October, 1896.

PATRICK H. PENDERGAST.

In presence of—

MARY A. FRANKLIN,
HOWARD P. DENISON.
